GARMENT CLASP

Eugene E. Norton, Bridgeport, Conn., assignor to
 Connecticut Clasp Company, Bridgeport, Conn.,
 a corporation of Connecticut

Application April 28, 1937, Serial No. 139,437

14 Claims. (Cl. 24—204)

This invention relates to clasps for garments such as corsets, in which the adjacent edges are brought together in edge-abutting relation.

An object of this invention is to provide a clasp which is easily manipulated to open and close the garment, yet which will not inadvertently open as a result of movements of the wearer's body.

Another object is to provide a clasp which, besides having the above advantages, is economical to make and to incorporate in a garment.

A further object is to provide a clasp which, while easily operated to close and open the garment, avoids tilting and incidental and annoying gaping prevalent in clasps other than the stud-type clasp in common use.

These and other objects of this invention are realized by features and advantages hereinafter appearing, including the provision of such co-operating clasp members on the adjacent flexible strips or stays that bowing of one member relative to the other is necessary to fasten or to undo the clasp, and no amount of bending of the two stays together and no tendency to move one stay bodily longitudinally of the other will cause the clasp to open.

An important feature of this invention is the provision of an improved undergarment clasp which has no outwardly projecting parts to show through the wearer's dress, or to touch any of the undergarments or the dress of the wearer and cause wear thereof.

In the accompanying drawing which discloses one form of this invention—

Figure 1 is a rear elevation of the adjacent edges of an open-front corset, showing the present invention as applied thereto, and showing a protective flap folded back.

Fig. 2 is a similar view, but showing the adjacent edges of the corset being brought together and the clasp partially in place.

Fig. 3 shows the clasp members of the present invention in the positions which they occupy prior to being fastened together, the adjacent portions of the corset being shown in dot-and-dash lines.

Fig. 4 is a transverse sectional view taken on the line 4—4 of Fig. 1.

Fig. 5 is a longitudinal section taken on the line 5—5 of Fig. 1.

Fig. 6 is an edge view of the clasp of the present invention, showing in dot-and-dash lines the position which one of the members must take in fastening and undoing the clasp.

Fig. 7 is a perspective view of one of the clasp members, showing its relation to the edge of the

corset within which it is placed, and showing a guard strip for preventing undue wear of the corset material by the other clasp member.

Fig. 8 is a view like Fig. 3, but showing the strips or stays of uniform width, rather than 5 tapered as in Fig. 3.

The clasp of the present invention is adapted to secure together the adjacent edges of any garment or the like, but is particularly advantageous when used to secure together the front opening 10 of a corset.

Accordingly, in the accompanying drawing, the clasp is shown as applied to a corset, the adjacent edges 10 and 11 of which are to be fastened together by the clasp. As is customary, 15 the edges 10 and 11 have provided within the material of the corset unjointed flexible strips or stays 12 and 13 respectively. These strips may be tapered upwardly as shown in Figs. 1, 2 and 3, or they may be of uniform width, as indicated at 20 12a and 13a in Fig. 8. The flexible portions of the corset below the strips 12 and 13 may be closed as usual by hooks and eyes 14.

Heretofore, the adjacent edges 10 and 11 of the corset were secured together by providing, on 25 say the flexible strip 12, a series of headed studs and providing, on say the strip 13, projecting ears having keyhole slots to receive the studs and hold the two strips together in substantial edge-abutting relation.

This form of clasp has been used for many years, for, while it was difficult at times to hook the studs and slotted ears together due to the fact that one might become unhooked while attempting to hook another, when all were hooked 35 the wearer had substantial security against the corset opening inadvertently, and, because of the number of studs and lugs, gaping of the corset at the open front with its consequent danger of pinching the body of the wearer was avoided. 40 But with this type of clasp the studs and slotted ears are exposed and frequently can be noticed especially when light clothing is worn. Besides, the exposed metal parts touch the undergarment or dress of the wearer and cause wear thereof. 45

The clasp of the present invention has no projecting metal parts which show or which engage the other clothing of the wearer and besides gives even greater security against the corset becoming inadvertently opened, and is a great deal 50 easier to fasten and undo than the common fastening heretofore referred to. This is because the corset, while maintaining the normal edge-abutting relation of the edges 10 and 11, is fastened and undone by a relative movement be- 55

tween the two edges 10 and 11 of the corset and especially between the two flexible strips 12 and 13 thereof, which movement is not reproduced by any movement of the body of the person wearing the corset.

To accomplish this, one of the flexible strips, the strip 12 in the form of the invention herein shown, is provided near its top end with a socket 15 and near its bottom end with a socket 16, and the other flexible strip, the strip 13 in the form of the invention shown, is provided with a tongue 17 near its upper end and a tongue 18 near its lower end. The tongue 17 is received by the socket 15 while the tongue 18 is received by the socket 16, and, when these tongues are properly located in their sockets, the edge 10 of the corset is securely fastened to the edge 11.

The sockets 15 and 16 and the tongues 17 and 18 are so arranged that they are on the inner side of the corset, leaving the outer side smooth and free of any projections.

According to the present invention in its broader aspects, the tongues 17 and 18 may be made a part of, or attached to, the flexible strip 13 in any desired manner, so that the tongues may lie in superposed relation to the strip 12 and may extend between the strip 12 (or the covering material overlying the strip 12) and the sockets 15 and 16. However, for reasons which will hereinafter appear, it is preferable that the tongues 17 and 18 be formed integrally with a third flexible strip 19 which may be fastened to the strip 13 by lugs 20.

In the form of the invention herein disclosed, three lugs 20 are provided, an upper, a lower, and an intermediate one. The upper and lower lugs 20 are so placed that when the two parts of the clasp are brought together as in Fig. 1, the upper edge of the upper lug 20 engages the lower edge 40 of the socket 15 while the lower edge of the lower lug 20 engages the upper edge of the lower socket 16, thereby limiting the longitudinal movement of the strip 12 relative to the strip 13. The upper and lower lugs need not, of course, be in direct contact with their related sockets 15 and 16, but they should be so disposed that the relative longitudinal bodily movement of the two strips 12 and 13 is so limited that the tongues 17 and 18 may not be withdrawn from their sockets 15 and 16 by such bodily longitudinal movement.

When it is desired to close the front opening of the corset, the tongue 17 is slid (by longitudinal movement of the strip 13 relative to the strip 12) into the socket 15, and this may be done even while the edge 11 of the corset is disposed at an angle to the edge 10, as illustrated in Fig. 2. The edge 11 is then swung toward the edge 10, and since, during this operation, the tongue 17 fulcrums on the socket 15, the operation is comparatively easy, even though considerable force is exerted thereby to tightly draw the corset around the body of the wearer, and this without danger of the tongue 17 slipping out of the socket 15. When the tongue 18 at the lower end of the clasp is superposed on the socket 16, pressure is exerted on the lower end of the flexible strip 13 so as to cause it to bow as shown in Fig. 6, thereby in effect shortening the flexible strip 13 and permitting the tongue 18 to be slid into the socket 16 when the bowing pressure is released. Likewise, in undoing the clasp, pressure is applied to the lower end of the flexible strip 13 independently of the strip 12 so as to bow the strip 13 and cause the tongue 18 to be withdrawn from the 75 socket.

With this form of clasp which requires the bowing of one of the strips or stays relative to the other, all danger of the clasp inadvertently or accidentally opening is avoided because any pressure on the lower portion of the garment resulting from the movements of the body of the wearer will cause both the strip 12 and the strip 13 to flex together, and when this occurs, the effective length of the two strips is maintained uniform and the tongues remain in the sockets. It is only by the deliberate and intentional bowing of one of the strips, the strip 13 in the instant case, relative to the strip 12, that the clasp can be fastened and unfastened.

By providing the strip 19 which carries at its upper and lower ends the tongues 17 and 18, and connecting this strip 19 to the strip 13 by the intermediate lug 20, tilting of the clasp with the consequent gaping of the opening is avoided. This is because when the garment is on the wearer and under a strain, such as would tend to cause tilting, the strip 19 is tightly pressed against the strip 12 or the intervening covering fabric so that the two are held relatively immovable, and, with the strip 19 so anchored, the intermediate lug 20 anchors the intermediate portion of the strip 13 to the strip 12.

When the corset is applied to the wearer, a soft protective flap 21 lies against the body of the wearer or the undergarments, and is in position to protect the body from contact with the clasp parts. Hence, in inserting the tongue 17 in the socket 15, it is guided into the socket between the flap 21 and the fabric of the corset overlying the strip 12. When the lower parts of the clasp are brought together, the tongue 18 and the flexible strip 19 likewise are covered by the flap 21 and do not contact with the body of the wearer.

Not only is the clasp of the present invention 40 advantageous from the point of operation and use, but also from the point of manufacture of the corset containing it, for, even though it is quite different in construction from the common stud-and-slot fastener above referred to, the 45 parts of the clasp may be contained within the edges 10 and 12 of the corset in substantially the same manner as the common clasp. For this reason, the sockets 15 and 16 are made in the form of ears, a portion 22 of which is secured to the 50 flexible strip 12, a portion 23 of which rises therefrom, and a portion 24 of which extends back upon the portion 22 in spaced relation and forms an open hook.

In making the corset, the folded-over top and 55 bottom fabrics 25 and 26 thereof are sewed together at their adjoining edges by stitching 25a (see Fig. 7) which is skipped at two places. The strip 12 is then inserted from the back and the sockets are passed through the portions which are skipped in the stitching. Then the top and bottom fabrics 25 and 26 are provided with a line of stitching 27 to hold the strip 12 close to the edge of the garment, and other lines of stitching 28 prevent longitudinal movement of the flexible strip 12 outwardly of the garment.

The corset-edge 11 is made substantially the same as the edge 10 above described, and is skip-stitched at portions 11a to leave slits for the lugs 20. To permit the flexible strip 13 to be inserted 70 between the layers or plies 29a and 29 of the corset at the edge 11, the flexible strip 19 is preferably made structurally separate from the strip 13 and the lugs 20, and is only fastened to the lugs after the lugs have been passed through the slits 75

left in the material of the corset by the skip-stitching. After the strip 13 is located in desired position, the strip 19 may be secured thereto by rivets 30.

5. Of course, if desired, the strip 19 may be initially secured to the strip 13, and the edge 11 may be sewed together by a special machine after the strip 13 is inserted between the upper and lower layers or plies 29a and 29 of the material.

10. In an expensive garment where fine or sheer material is employed, there may be danger of damaging the material and causing it to become frayed as a result of repeated insertions of the tongue 18 in the socket 16, especially because of the fact that the strips 13 and 19 are bowed at the time the tongue enters the socket. To avoid this,

15. the present invention provides a protective strip of metal 31 in the vicinity of the socket 16. This tongue may be secured in place in any desired way, but, according to the present invention, it is preferably carried by the flexible strip 12 and in such a way that it may be placed in operative position very conveniently. Since the guard strip 31 is carried by the flexible strip 12, to be effective, it must extend through the fabric 25 cov-

20. ering the strip 12. To permit this to be done, the fabric 25 is provided with slits 32, preferably protected by buttonhole stitching. After the edges of the fabrics 25 and 26 have been skip-

25. stitched as above explained, they are laid out flat and the guard strip 31, which is pivotally mounted at 33 on the strip 12, is swung outwardly away from the socket 16 so that it may, with convenience, be passed out and in through the

30. slits 32. When this is done, the guard strip 31, with the material coupled to it by the slits 32, is swung to bring its edge in alignment with the edge of the flexible strip 12, that is, to the position shown in Fig. 7, and this, at the same time,

35. causes the socket 16 to extend through the slit provided in the covering by the skip-stitching above referred to. The flexibility of the material then permits the socket 15 to be extended through its slit in the seam, and after this the fabrics 25

40. and 26 are brought together and sewed at 27 as above stated.

In the form shown, the strips 12 and 13 are surrounded by covering strips 34 of heavy material.

50. In the broader aspects of the invention, the guard strip 31 may, of course, be omitted, its function being merely to prevent the tongue 18 from damaging the fabric and causing it to fray.

What has been said about the strips 12 and 13 applies in every respect to the strips 12a and 13a of Fig. 8.

Variations and modifications may be made within the scope of this invention and portions of the improvements may be used without others.

60. I claim:

1. A corset-front clasp comprising a plurality of flexible unjoined strips, the first strip and the second strip being secured to the corset at adjacent sides respectively of the opening to be closed and lying in substantially edge-abutting relation when in operative position, and the third strip being fastened to the first strip and underlying the second strip in superposed relation when in operative position, said second strip having a 65 socket adjacent one end of the same adapted to slidably receive a tongue on the third strip while the first and second strips are angularly disposed and about which the first and second strips may fulcrum when closing the opening and forcefully 70 tightening the corset around the body of the

wearer and having a socket adjacent the other end thereof to receive a tongue on the corresponding end of the third strip, when the latter is shortened by bowing the same relative to the second strip, to hold said first and third strips 5 to the second strip against movement apart; and means for preventing such relative longitudinal bodily movement between the first strip and the second strip as would permit said tongues to be withdrawn from the sockets. 10

2. The invention as defined in claim 1, in which the last-named means includes straps connecting the first and third strips together.

3. The invention as defined in claim 1, in which the first and second strips are adapted to 15 be enclosed within the fabric of the adjacent sides of the garment with the third strip and the sockets on the second strip exposed for direct engagement with each other.

4. The invention as defined in claim 1, in 20 which the first and second strips are adapted to be enclosed within the fabric of the adjacent sides of the garment with the third strip and the sockets on the second strip exposed for direct engagement with each other, in which a piece of 25 metal is superposed on the fabric covering the second strip in the vicinity of the one of said sockets which receives the tongue on the third strip after the latter is bowed, to protect the garment from being damaged by the said tongue. 30

5. The invention as defined in claim 1, in which the sockets on the second strip are constituted by ears projecting from the second strip and each extending back upon itself to provide an open hook adapted to be passed through slits 35 left open in the sewed end of the fabric of the end of the garment carrying and enclosing the second strip.

6. A corset-front clasp comprising a pair of 40 flexible unjoined strips secured respectively to adjacent sides of the opening to be closed and lying in substantially edge-abutting relation when in operative position, one of said strips having a socket adjacent each end thereof; laterally extending straps secured to the other strip 45 to underlie the socket-carrying strip; and tongues carried by said laterally extending straps, each adapted to be received by one of said sockets, the distance between the outer ends of the straps being such that one of said tongues is adapted 50 to be inserted in its associated socket by relative longitudinal movement between the strips and the other tongue being insertable in its socket and removable therefrom only when the strip carrying the tongues is bowed relative to the 55 strip carrying the sockets.

7. A corset-front clasp comprising a pair of 60 flexible unjoined strips secured respectively to adjacent sides of the opening to be closed and lying in substantially edge-abutting relation when in operative position; cooperating means at one end of the strips adapted to be engaged by bodily longitudinal movement of the strips relatively in one direction to hold closed that end of the opening; and cooperating means at the other end of the strips and so spaced from said first-mentioned means that they are adapted to be engaged and disengaged only by bowing movement of one strip relative to the other to hold closed the other end of the opening. 65

8. A corset-front clasp comprising a pair of 70 flexible unjoined strips secured respectively to adjacent sides of the opening to be closed and lying in substantially edge-abutting relation when in operative position; cooperating means at one 75

end of the strips adapted to be engaged by bodily longitudinal movement of the strips relatively in one direction to hold closed that end of the opening; and cooperating means at the other end of the strips and so spaced from said first-mentioned means that they are adapted to be engaged and disengaged only by bowing movement of one strip relative to the other to hold closed the other end of the opening, said strips being held against relative longitudinal bodily movement by both said cooperating means when the clasp is closed.

9. A corset-front clasp comprising a pair of flexible unjointed strips secured respectively to adjacent sides of the opening to be closed and lying in substantially edge-abutting relation when in operative position, one of said strips being provided with sockets adjacent the ends thereof; tongues each adapted to be received by one of said sockets and carried by and extending laterally from the other strip to underlie the socket-carrying strip, one of said tongues being adapted to be inserted in its associated socket by relative longitudinal movement between the strips and the other tongue being insertable in its associated socket and removable therefrom only when the strip carrying the tongues is bowed relatively to the strip carrying the sockets; and means on one strip and underlying the other strip and which when pressed together by pressure of the wearer's body holds the two strips together against tilting and gaping at points intermediate said sockets and tongues.

10. A corset-front clasp comprising a pair of flexible unjointed strips secured respectively to adjacent sides of the opening to be closed and lying in substantially edge-abutting relation when in operative position; cooperating means at one end of the strips adapted to be engaged by bodily longitudinal movement of the strips relatively in one direction to hold closed that end of the opening; cooperating means at the other end of the strips so spaced from said first-mentioned means that they can be engaged and disengaged only by bowing movement of one strip relative to the other to hold closed the other end of the opening; and means between the ends of said strips cooperating to prevent tilting of said strips and consequent gaping of the adjacent edges of the corset.

11. A corset-front clasp comprising a pair of flexible unjointed strips secured respectively to adjacent sides of the opening to be closed and lying in substantially edge-abutting relation when in operative position; cooperating means at one end of the strips adapted to be engaged by bodily longitudinal movement of the strips relatively in one direction to hold closed that end of the opening; cooperating means at the other end of the strips so spaced from said first-mentioned means that they are engaged and disengaged only by bowing movement of one strip relative to the other to hold closed the other end of the opening; and a third strip secured to the side edge of one of the first-mentioned strips to be coextensive therewith and to underlie the other of said strips so that pressure exerted by the body of the wearer on said third strip urges it against its overlying strip, and prevents relative angular movement between the first-mentioned strips, and consequent gaps in the opening of the corset.

12. A corset-front clasp comprising a plurality of flexible unjointed strips, the first strip and the second strip being secured to the corset at adjacent sides respectively of the opening to be closed and lying in substantially edge-abutting relation when in operative position; a third strip; means for fastening the third strip to the first strip, including tongue-defining straps, the tongues having free ends oppositely directed, said third strip underlying the second strip in superposed relation when in operative position; and sockets spaced apart longitudinally of said second strip for interlocking relationship with the tongues of the third strip, the distance between the inner ends of the sockets being substantially equal to the distance between the outer ends of the tongue-defining straps, whereby the tongues of the third strip are engageable with the sockets of the second strip only by a combination of bending and longitudinal movement of the third strip relative to the second strip.

13. A corset-front clasp comprising a plurality of flexible unjointed strips, the first strip and the second strip being secured to the corset at adjacent sides respectively of the opening to be closed and lying in substantially edge-abutting relation when in operative position; a third strip; and means for fastening the third strip to the first strip, including tongue-defining straps, the tongues having the free ends thereof oppositely directed, said third strip underlying the second strip in superposed relation when in operative position, said second strip having sockets spaced apart longitudinally of the same for interlocking relationship with the tongues of the third strip, the distance between the outer ends of the tongues being greater than the distance between the inner ends of the sockets, and the distance between the outer ends of the tongue-defining straps and the inner ends of the sockets being substantially equal, whereby the tongues of the third strip are engageable with the sockets of the second strip only by a combination of bending and longitudinal movement of the third strip relative to the second strip, the straps provide an impositive stop means for precluding accidental or casual movement.

14. A corset-front clasp comprising a plurality of flexible unjointed strips, the first strip and the second strip being secured to the corset at adjacent sides respectively of the opening to be closed and lying in substantially edge-abutting relation when in operative position; a third strip; means for fastening the third strip to the first strip, including tongue-defining straps, the tongues having free ends oppositely directed, said third strip underlying the second strip in superposed relation when in operative position; and sockets spaced apart longitudinally of said second strip for interlocking relationship with the tongues of the third strip, the distance between the inner ends of the sockets being substantially equal to the distance between the outer ends of the tongue-defining straps, said straps being adapted to provide an impositive stop means for preventing accidental or casual relative movement of said strips after the tongues of the third strip are in engagement with the sockets of the second strip.
